UNITED STATES PATENT OFFICE

2,465,440

RAZOR CLEANING DEVICE

Joseph P. Fleckenstine, Glendale, Calif.

Application June 20, 1946, Serial No. 678,118

4 Claims. (Cl. 15—218)

1

This invention relates to devices for cleaning and drying razor blades, and the embodiment of the invention herein shown is designated particularly for use with double edged blades. In my Patent No. 2,187,491, dated January 16, 1940, I have disclosed a razor cleaning device consisting of a pair of wiping or drying pads each composed of a layer of absorbent material, such as Canton flannel attached to a layer of stiffer backing material such as fiber board. The pads are secured face to face and arranged to permit a wet razor blade to be passed between them for drying contact with their absorbent surfaces. This is much more efficient and less dangerous than the common expedient of attempting to dry the blade with an ordinary towel and it avoids the damage to the towel which frequently results from that method.

The present invention is directed to increasing the convenience and efficiency of the drying device of my said patent.

One object of the invention is to provide a substantial and durable case to serve as a holder for a pair of razor cleaning pads similar to those disclosed in my said patent.

Another object of the invention is to provide a new and improved razor cleaning device which includes a pair of absorbent pads and a holder in which said pads are disposed face to face and correctly spaced to receive a razor blade between them for wiping engagement therewith.

It is also an object of the invention to provide a razor cleaning device which includes a pair of absorbent pads and a holder in which said pads are disposed face to face and gripped to prevent dislodgment of the pads from the holder when a razor blade is passed between them.

A further object of the invention is to provide a new and improved holder for a pair of absorbent pads to be arranged face to face therein for wiping engagement with a razor blade to be passed between them, including in said holder blade guiding means which insures correct placement and entry of the blade between the pads in the holder.

An additional object of the invention is to provide a new and improved holder for a pair of absorbent pads to be secured therein face to face for wiping engagement with a razor blade, and to include in said holder means for exerting special pressure on the pads in the vicinity of the margins of the blade as it passes between them to insure good wiping contact at the cutting edges of the blade.

Other objects and advantages of the invention

2

will appear from the following description taken in connection with the drawings, in which:

Fig. 1 is a perspective view showing a case embodying one form of the invention with absorbent pads installed therein;

Fig. 2 is a front elevational view of the device shown in Fig. 1;

Fig. 3 is an end elevation of the same;

Fig. 4 is a bottom plan view;

Fig. 5 is a vertical sectional view taken as indicated at line 5—5 on Fig. 2;

Fig. 6 is a fragmentary detail section taken as indicated at line 6—6 on Fig. 2;

Fig. 7 is a perspective view of a modified form of the invention with portions of the case and a portion of one of the absorbent pads broken away;

Fig. 8 is a fragmentary vertical section taken as indicated at line 8—8 on Fig. 7;

Fig. 9 is a top plan view of the device shown in Fig. 7 but on a reduced scale;

Fig. 10 is a perspective view of the absorbent pads of the type for which the case shown in Fig. 7 is designed.

In my Patent No. 2,187,491 above mentioned, the razor blade drying and cleaning device was shown simply as a pair of absorbent pads, each provided with a backing member and secured together by a suitable adhesive at two opposite margins, leaving the remainder of the opposed areas of the absorbent members available to receive a razor blade between them. To facilitate the handling of such a device and to protect the pads when the device is not in use, the present invention provides a case 10, such as that shown in Figs. 1 to 6. This case is preferably a unitary structure of relatively flat tubular form and may be die cast of suitable metal or may be molded of plastic material. As shown in Fig. 5, the front

wall 12 and the back wall 14 are spaced apart by a suitable distance to accommodate between them the absorbent pad 16 with its backing member 18 to which it is adhesively secured, and the absorbent pad 20 with its backing member 22

to which it is also adhesively secured. Along their upper edges the pads and their respective backing members are bound together by strips of waterproof tape preferably made of moisture proof cellulose acetate. This prevents the edges

of the absorbent material of the pads 16 and 20 from being exposed at these marginal portions of the pads between which the razor blade is entered for its wiping engagement with the opposing absorbent faces.

Before insertion in the case 10, the two absorbent

55

ent pads with their backing members are secured together as a unit by suitable adhesive which connects them at two opposite margins, leaving the upper margins which are covered by the tapes 24 substantially unattached and leaving the opposite lower margins also unconnected. This assembled unit or filler is then slidably inserted into the tubular case 10 from the open lower end thereof. At the upper end the front fall 12 has an inturned lip 26 serving as a stop for the pad 16, and its backing member 18 and the back wall 14 has a similar inturned lip 28 serving as a stop for the upper edges of the pad 20 and its backing member 22. The pad 20 is slightly higher than the pad 16 so that its taped upper margin projects above the taped upper edge of the pad 16 and facilitates inserting the end of a razor blade between the pads in position to be passed through the device in wiping contact with their opposing absorbent faces. The total height of the device is less than the length of a blade so that as the advancing end of the blade emerges from the lower end of the case 10, it can be grasped and withdrawn.

As shown in Fig. 4, the inner surfaces of the walls 12 and 14 of the tubular case 10 are provided with ribs 30 extending vertically and projecting toward each other, the ribs of the wall 12 being registered with those of the wall 14, and the two ribs on each wall being spaced apart by approximately the width of a razor blade. Thus when such a blade A is presented to the upper end of the case 10 in the position shown in Fig. 2 and is then pushed through the case between the opposing faces of the pads 16 and 20, these faces will be held most firmly in contact with the marginal portions of the blade adjacent its cutting edges so as to insure thorough drying of the blade surfaces at these areas. The case 10 can be die cast or molded with sufficient accuracy to provide uniform spacing between the opposing ribs 30 with a tolerance not exceeding .005 of an inch so as to insure proper engagement of the pad with a blade of standard thickness. The resilience of the absorbent material, however, will be sufficient to accommodate blades which differ slightly in thickness from those which may be considered standard.

Adjacent to the narrow side walls 32, 32 of the case 10, the ribs 34, which project from the inner surfaces of the front wall 12 and back wall 14, are slightly higher than the ribs 30 so as to grip the marginal portions of the pad assembly, compressing it sufficiently to insure that the friction between the surface of the blade and the absorbent pads will not dislodge the pad structure from the case as the blade is passed through it. To facilitate entry of the pad assembly through the lower end of the case, the lower ends of these ribs 34 may be tapered divergently as shown in Fig. 6.

In the aforesaid Patent No. 2,187,491, an alternative form of dryer is shown in which the two pads are identical in area but have their taped margins spread apart slightly to form a mouth or entrance opening at which the end of the blade may be introduced between the pads. Figs. 7, 8 and 9 illustrate a slightly modified form of case 40 for use with this alternative type of drying unit. The general outlines of the case 40 are similar to those of case 10, except that its front wall 42 is equal in area to its back wall 44, and instead of mere lips or flanges at the upper ends of these walls, the case includes an integral top wall 46 having a slot 48 to receive the end

of the razor blade. Fig. 10 shows a pad assembly or filler unit consisting of a front panel 50 and a back panel 52, each composed of an absorbent layer and a stiffening layer, as in the structure shown in Fig. 5, and each having a tape 54 applied as a binding over its upper edge. The middle portions of the upper edges of the panels 50 and 52 are bent outwardly at 56 forming between them the mouth or entrance opening 58. When this unit is inserted in the case 40, the opening 58 registers therein with the slot 48 in the top wall 46 in position to receive the end of a razor blade as it is passed through the device for wiping engagement with the absorbent surfaces of the pad panels 50 and 52. In Fig. 7, a portion of the front wall 42 is broken away to show the panel 50 and a portion of this panel is broken away revealing the absorbent surface of the panel 52 in operative position within the case 40.

To further insure the proper positioning of the mouth 58 of the unit within the case 40, the top wall 46 is provided with depending lips or flanges 60 and 62 which respectively engage the upper edges of the pad panels 50 and 52 to insure that the spaced portions 56, 56 of these parts shall remain separated and shall be held at opposite sides of the slot 48. At each end of the guideway or finder slot 48, the opening in the top wall 46 is continued in the form of narrow slots 49, the end portions of the slot 48 being tapered at 51 to merge with the narrower slots 49. This insures that if a blade is not entered quite straight in the guide slot 48, one cutting edge of the blade will be accommodated in one of the narrower slots 49 and will thus avoid dulling contact with the material of the case. It is desirable, of course, that the blade be passed through the device in a direction parallel to its cutting edges so that said edges will not tend to shear away the surface fibers of the absorbent pads, and with the centering and guiding effect of the entrance slot 48 and mouth 58, this result is practically assured. However, the width of the pads is such that a slightly angular position of the blade with relation to its direction of movement is not prevented and will not result in any injury to its cutting edges.

To further assist the user in properly entering the blade at the slot 48, an upstanding guide flange 64 may be provided at one side of the slot 48 as shown in Fig. 7 and 8, the face of this flange 64 functioning in substantially the same manner as the extra height of the pad 20 in the form shown in Fig. 5. The interior of the case 40 may include ribs 66 arranged to hold the pads 50 and 52 in close engagement with a blade passed between them, but in view of the flared upper portions of the pads forming the mouth 58, the ribs 66 may terminate at a distance below the end wall 46 of the case. Additional ribs 68 may be provided adjacent to the narrow side walls 43 as indicated in dotted outline in Fig. 7. The lower ends of the case 40 will be made open over its entire cross section like the lower end of the case 10 to permit insertion of a pair of pads 50 and 52 or withdrawal of the pads when they require replacement.

While there are shown and described herein certain structures embodying my invention, it is to be understood that the invention is not limited thereto or thereby, but embraces all modifications, variations and equivalents which may come within the scope of the appended claims.

I claim:

1. A blade cleaning device comprising, in combination, a flat tubular case open at one end, said

case having a wall at the opposite end with a slot in said wall, and a pair of wiping pads in said case, each pad comprising a layer of absorbent material, a stiffening layer adhesively secured thereto, and a binding strip overlapping both layers at one edge, said pads being disposed in the case with their absorbent surfaces in face to face relation and with their bound edges adjacent to said slot in position to receive a blade between them, said case having an upstanding guide flange projecting from the end wall, said flange having a surface continuous with one edge of said slot to facilitate entry of a blade therein.

2. A device of the class described, comprising a flat tubular case having relatively wide front and back walls and relatively narrow side walls joining them, said case being open at both ends but including inwardly extending abutment means at one end to limit the insertion of drying pads from the other end of the case, said front and back walls of the case having mutually opposed ribs extending longitudinally and projecting from their inner surfaces, said ribs being dimensioned to engage said pads between them, two of said ribs on each wall being disposed adjacent said side walls respectively and being higher than the other ribs for gripping the marginal portions of the pads between them.

3. In a device as defined in claim 2, each pair of higher ribs adjacent the side wall of the case having tapered, divergent end portions at the

open end of the case to facilitate entry of the pads between said ribs.

4. A blade cleaning device comprising, in combination, a flat tubular case open at one end, said case having a wall at the opposite end with a slot in said wall, a pair of wiping pads in said case, each pad comprising a layer of absorbent material, a stiffening layer adhesively secured thereto, and a binding strip overlapping both layers at one edge, said pads being disposed in the case with their absorbent surface in face to face relation and with their bound edges adjacent to said slot in position to receive a blade therebetween, said case having inwardly extending flanges at both sides of said slot to engage said pads at their bound edges and insure separation of said edges of the pads in the vicinity of the slot.
